US00D453629S

(12) **United States Design Patent** (10) Patent No.: **US D453,629 S**
Kraker (45) Date of Patent: ** Feb. 19, 2002

(54) **PATTERN FOR A SYNTHETIC THERMOSET SOLID SURFACE MATERIAL**

(76) Inventor: **Patrick O. Kraker**, 1700 Westminster Pl., Oklahoma City, OK (US) 73120

(**) Term: **14 Years**

(21) Appl. No.: **29/137,410**

(22) Filed: **Feb. 20, 2001**

(51) LOC (7) Cl. **05-06**

(52) U.S. Cl. **D5/43**

(57) **CLAIM**

The ornamental design for a pattern for a synthetic thermoset solid surface material, as shown and described.

DESCRIPTION

The file of this patent contains at least one photograph executed in color. Copies of this patent with a color photograph will be provided by the Patent and Trademark Office upon request and payment of the necessary fee.

The sole FIGURE is a top plan view of a pattern for a synthetic thermoset solid surface material, showing our new design.
